United States Patent Office.

THEODORE GRUNDMANN, OF CLEVELAND, OHIO.

Letters Patent No. 82,712, dated October 6, 1868.

IMPROVED APPARATUS FOR THE MANUFACTURE OF VINEGAR.

The Schedule referred to in these Letters Patent and making part of the same.

TO ALL WHOM IT MAY CONCERN:

Be it known that I, THEODORE GRUNDMANN, of Cleveland, in the county of Cuyahoga, and State of Ohio, have invented a new and useful Improvement in Filtering and Vinegar-Apparatus; and I do hereby declare that the following is a full, clear, and exact description thereof, which will enable others skilled in the art to make and use the same, reference being had to the accompanying drawings, forming part of this specification, in which—

Figure 1 represents a side elevation of my improved filtering-apparatus.

Figure 2 is a vertical central section of the same.

Figure 3 is a plan or top view, partly in section, of the same.

Figure 4 is a detail vertical section of the automatic mash-distributer in the vinegar-apparatus.

Similar letters of reference indicate corresponding parts.

This invention relates to a new apparatus for making vinegar from suitable fermented liquids.

It consists, first, in substituting, for the shavings generally employed, braided straw, cotton or hemp strings, which are held suspended, and along which the liquid has to flow down in small streams.

The invention consists, second, in the construction and arrangement of an automatic distributer, which is a pivoted box, divided into two compartments. The liquid flows into one compartment, and its weight, when it has filled such compartment, swings the box around the pivot, so as to bring the other empty compartment under the supply-pipe, while that previously filled is emptied into the apparatus.

The invention also consists in the construction of the whole apparatus, which can be easily taken apart and put together.

The invention consists, finally, of a filter, through which the mash is passed preparatory to its passage to the vinegar-apparatus.

A, in the drawing, represents a box or case, made of wood, or other suitable material, of prismatic form, open at both ends, *i. e.*, at the upper and lower ends.

This box is constructed by connecting its sides, by means of hooks *a a*, or their equivalents, in such manner that it can be readily taken apart.

The box is set upon a vessel, B, for receiving the liquid, and for closing its lower end.

Within the box A is set up or arranged a frame, C, which may, if desired, be simply a frame of slats, resting on lugs that project from the inner sides of the box, or which may be provided with legs *b b*, as shown.

From the slats of the frame C is suspended a series of braided strands, D D, which are either made of straw, flax, hemp, or other suitable material, as is clearly shown in fig. 2.

Upon the frame C is placed a woven sheet, E, made of straw, or other material, or any other suitable porous fabric.

Above the sheet E is arranged, within the box A, a perforated horizontal plate, F, as shown in figs. 2 and 4. From this plate F project upward two lugs *c c*, which support a swinging box, G.

The box G is pivoted between and to the lugs *c*, and is composed of two equal triangular compartments *d e*, as in fig. 4, that are open on top.

If the box is turned to one side, so that the outer wall of the compartment *e* rests on the plate F, as in fig. 4, the other compartment *d* will be in position to receive the liquor, which is brought to it through a pipe, *f*, from the filter H, said pipe discharging the liquor into a funnel, *g*, formed on the covering-plate *h* of the box A.

When the compartment *d* has been filled, its weight causes the box G to turn over, so as to bring the other compartment *e* under the funnel, while the contents of *d* will be poured over the plate F, whence they pass through the sheet E, and then flow gradually down the strands D. On these strands, the liquid is exposed to a draught of air, which enters the lower part of the box A, through a pipe, *i*, and the liquid is thus, in small streams, that flow slowly along over and through the windings of the strands, amply oxygenated.

The liquor—thus acidified is drawn off the vessel B through a pipe, *j*.

The draught and temperature in the box A can be regulated by means of dampers *k k*.

By having the box G automatically operating, as described, the liquid will not be continuously discharged into the apparatus, but there will be, after a portion has been emptied from a compartment, *d* or *e*, some time left for the liquid to clear the plate F, and sheet E.

The filter H is a vessel, of suitable size and shape, provided with two perforated false bottoms, *l* and *m*, between which saw-dust, shavings, or other equivalent material is compressed. The mash is poured upon the upper plate *l*, has then to work through the filling, and through the plate *m*, and arrives in the lower compartment *n* of the filter, whence it is, through the pipe *f*, conducted to the hopper.

Having thus described my invention, I claim as new, and desire to secure by Letters Patent—

1. The braided strands D D, when used in a vinegar-apparatus, for spreading the mash, and exposing it to the air, as set forth.

2. The self-regulating swinging mash-distributing box G, arranged substantially as herein shown and described.

3. The box A, when composed of a series of detachable plates, as set forth, so that the suspended braids D may be exposed to the air to be dried.

4. A vinegar-apparatus, consisting of the box A, vessel B, frame C, braided pendants D, distributing-box G, and supply and discharge-pipes *f* and *j*, all made and operating substantially as herein shown and described.

5. The device set forth in the foregoing clause, in combination with the filter H, in which the two perforated plates *l* and *m* are arranged, as set forth.

6. The distributing-sheet E, arranged between the swinging box G and the braided pendants D, substantially as herein shown and described.

THEODORE GRUNDMANN.
